2,024,493

REFRIGERATOR EVAPORATOR DOOR

Walter H. Weinrich, Chicago, Ill., assignor to
Stewart-Warner Corporation, Chicago, Ill., a
corporation of Virginia

Application December 18, 1933, Serial No. 703,024

5 Claims. (Cl. 220—32)

My invention relates to a detachable door and particularly to a detachable door for use in the evaporator of a refrigerator.

In modern domestic refrigerators, it is customary to provide an enameled evaporator, fabricated of stamped metal. The stampings are so made that conduits or passages are formed through which the refrigerant circulates about an internal freezing compartment, in which trays 5 of water or food may be placed for freezing. To facilitate this freezing, it is desirable to provide a closure for this internal compartment in order to prevent the circulation of the warmer outside air into the freezing chamber.

10 The use of this kind of evaporator, however, makes it difficult to attach a door or closure for the freezing compartment. In the first place, it is undesirable to make any perforations for rivets or screws, because the danger of causing a leak through which refrigerant gas may escape. Furthermore, the fact that the evaporator is to be 15 enameled makes it difficult to apply any supports or hinges for a door because of the fact that it is difficult to secure an even coat of enamel over 20 small and irregularly shaped parts, and also because of the fact that the enamel is likely to clog or obstruct any openings in the supporting parts, for example, the opening for receiving a hinge pin. If the attempt is made, after the 25 enameling has been completed, to attach a door support in some conventional manner, it is likely that the enamel will be chipped or marred.

30 My invention not only overcomes these difficulties, but provides several additional valuable novel features. Some users may wish to dispense with the door entirely for reasons of convenience, even though this may sacrifice the speed and economy with which the water may be frozen within the compartment. My door is readily detachable so that this may be accomplished. Moreover, my door may be attached to 35 either side of the evaporator so that it may open in either direction. This is desirable because of the fact that refrigerators are usually sold with the main door opening from the right or left hand at the buyer's option, and it is desirable that the door of the freezing compartment should open in the same direction as the main door in order that the closing of the main door will also close the freezing compartment door instead of knocking against it in case it is inadvertently left open. With this feature of my invention it is unnecessary to provide a different evaporator and door structure for right and left hand main 40 doors.

In addition to the above features, it will be seen that the door I have provided is very simple, neat, and inexpensive to manufacture.

A thorough understanding of my invention may be had by reference to the accompanying drawing, in which

Figure 1 is a perspective view of the evaporator and door combination;

Figure 2 is a detail section showing the latching of the hinge for the door upon the evaporator, 10 and

Figure 3 is a detail section showing the mounting of the hinge for the door upon the evaporator.

Referring now to Figure 1, evaporator 10, having conduit portions 12 and fitted with an ice 15 tray receiving shelf 14, is illustrated in connection with a conventional refrigerator cabinet. As a closure for the compartment 16, I have provided a stamped metal door 18, which carries hinge straps 20.

To form a hinge support, I have provided a hinge clip, 22, formed with flat internal portions 24 and an outer portion 26 suitably shaped to be clipped over the outer face of the evaporator. Formed as part of the clip by stamping, I have 25 provided ears 28, through which hinge pins 30 are passed. These hinge pins are riveted at their ends to hold them in place.

It will be noticed that spaces are left between the inner flat portions 24. These spaces are 30 left in order that the clips may be attached to the evaporator without interference with the shelf 14. It will be apparent that if the door is to be attached to the opposite side of the evaporator than is shown, the door must be inverted, and it is 35 for this reason that the second space is left. Various other arrangements to accommodate shelves at various positions will suggest themselves.

A knob 32 is attached to the door by a screw 40 34, which also holds in place a spring latch 36.

To engage the latch and hold the door in place, a latch clip 38 is provided which is substantially similar to the hinge clip 22. However, this latch clip is formed with an in-turned lip 40, which 45 serves to engage the spring latch 36.

As a stop for the door to prevent the door's swinging too far open, I have provided lugs 42 which are stamped out of the hinge clips 22.

It will be seen that in order to attach my door 50 to an evaporator, the hinge clip together with the door is clipped over one edge of the evaporator, the latch clip is placed over the opposite edge. The door may then be opened or shut as desired. It will be seen that this has been ac-

complished in a very simple manner, without perforation of the evaporator and without damage to the enamel. It will also be seen that if desired the door may be made to swing from either side of the evaporator, or, if desired, it may be removed entirely.

5 While I have described this specific embodiment of my invention, it should be understood that I do not intend to limit myself except to the spirit 10 of my invention herein described.

I claim:

1. In combination, a closed housing having an open end, a door adapted to close the open end of said housing and a hinge member carried by 15 said door, said hinge member having spaced clip portions for engaging said housing to mount said door thereon, a latch fixed to said door and a latch clip detachably secured to said housing for engagement with said door latch.

20 2. In combination with a chambered casing having an open end, said casing having a corrugated surface, a door adapted to close the open end of said casing, a hinge member pivotally secured to said door, said hinge member having spaced clip portions for detachable securement to a corrugation at one edge of said casing, a handle for said door, a latch for said door and a latch clip detachably secured to a corrugation at an opposite edge of the casing and adapted 25 to engage said door latch.

30 3. In combination with a casing having an open end, said casing having a vertical corrugation

along one exterior side thereof adjacent the open end of said casing, a door for said casing, a hinge member pivoted to said door at spaced points, spaced clip means on said hinge member, each of said clip means including a tongue adapted to fit into the chamber of said casing and engage the inner surface of a side wall thereof, and a second tongue adapted to engage the exterior surface of said side wall, said second tongue being bent to engage said corrugation to detachably 10 secure said hinge member to said casing.

4. A detachable hinge comprising spaced internal and external portions integrally connected and adapted to be clipped to the edge of a casing, outturned lugs on the external portion with 15 aligned openings and a hinge pin in said openings, and a struck-up tongue formed in the external portion and extending outwardly of the hinge pin to act as a stop for a door secured to said hinge pin.

5. A detachable hinge comprising spaced internal and external portions integrally connected and adapted to be clipped to the edge of a casing, said outer clip being concave inwardly to fit over a bend or corrugation adjacent an edge 25 of the casing, outturned lugs on the external portion with aligned openings and a hinge pin in said openings, and a struck-up tongue formed in the external portion and extending outwardly of the hinge pin to act as a stop for a door se- 30 cured to said hinge pin.
